UNITED STATES PATENT OFFICE.

HENRY RIDGEWAY HART, OF MONTCLAIR, NEW JERSEY.

PLAYING DEVICE.

Application filed July 9, 1923. Serial No. 650,537.

To all whom it may concern:

Be it known that I, HENRY RIDGEWAY HART, a citizen of the United States, residing at Montclair, in the State of New Jersey, have invented certain new and useful Improvements in Playing Devices, of which the following is a specification, reference being had to the accompanying drawing, forming a part hereof.

10 This invention relates to valves and more particularly to valves secured to the bladders of footballs, basketballs, punching bags and other inflatable devices used in athletic pastimes.

15 In application No. 528,433 filed January 11, 1922, there is disclosed a valve in which the valve tube is secured in a hole in the bladder by clamping devices to form an air-tight joint with the bladder and in which

20 a valve cap is threaded into the end of the valve tube and has a broad flat head rounded to conform to the underside of the cover of the inflatable device. Devices of this nature are always provided with a

25 tongue adapted to close the opening in the cover through which the bladder is inserted and this tongue is formed with a hole through which the stem of the bladder or the valve tube is adapted to pass for positioning the bladder within the cover and to facilitate inflation of the bladder. In the above mentioned application the valve tube is disclosed as passing through the hole in the tongue and secured thereto by means

30 of the valve cap which clamps the tongue between itself and the aforementioned clamping devices securing the tube to the bladder. It has been found in practice that when the valve cap is removed for the

35 purpose of inflation the tube is likely to slip out of the hole in the tongue due to the partially deflated bladder changing its position within the cover. The present invention seeks to provide means for

40 securing the valve tube to the tongue independently of the valve cap so that the tube will always be maintained in place and the bladder never shift from its proper position in the cover. Accordingly an additional clamping member is

45 provided which is adjustable with respect to the valve tube and is adapted to clamp the tongue between itself and the clamping devices gripping the bladder so that the

50 tube is always maintained in the hole in

the tongue irrespective of the presence of the cap on the tube.

In order that the present invention may be clearly understood reference will now be had to the following description of a preferred embodiment thereof as applied to a football which is illustrated in the accompanying drawings and in which:

Fig. 1 is a view in plan of an inflated football embodying the invention, the head of the valve cap being indicated in dotted lines.

Fig. 2 is a detail view in sections and on a somewhat larger scale showing the relation between the bladder, the valve tube and the cover, and taken on the plane indicated by the line 2—2 in Fig. 1 and looking in the direction of the arrows.

Fig. 3 shows in perspective the valve tube with the clamping nut and washer by which it is united with the bladder, the clamping nut by which it is united to the tongue of the cover and the valve cap.

As indicated in Figure 2, the bladder *a* is of the form illustrated in the aforementioned application and formed with a plain hole *a'* therein of such dimensions as to receive the upper threaded end *b'* of the valve tube *b*. The end of the stem of the valve is indicated at *c*. The tube *b* carries a rimmed flange *b*² which, when the valve tube is in place, lies against the inner wall of the bladder *a* immediately around the hole *a'*.

A slightly flexible washer *d* of metal or other suitable material is adapted to fit down over the threaded end *b'* of the valve tube and overlie the outer surface of the bladder *a* immediately around the hole *a'*. This washer *d* may also be formed with a rim *d'* for engagement with the yielding rubber of the bladder *a*. The clamping means is found in nut *e* which is threaded down on to the end *b'* of the tube to lie against washer *d* and squeeze the rubber between the flange *b* and washer *d* to form mechanically an airtight joint. Holes *e'* may be formed in the nut *e* for engagement by a spanner wrench. In inserting a bladder having a valve tube of this nature in a football the bladder is inserted in a deflated condition in the cover *f*. The opening *f'* in the cover is closed by a tongue *f*² carried with the cover and preferably having a lining *f*³ of felt or like material. This tongue is

formed with a hole f^4 through which the valve tube is adapted to project. In order to maintain the bladder in proper position in the cover with the valve tube protruding through the hole f^4 , means is provided on the valve tube to engage the tongue immediately around the hole. For this purpose a nut g is threaded over the end b' of tube b and clamps the tongue between itself and the nut e and washer d . Holes g' may be formed in the nut g for engagement by a spanner wrench. It will be noticed that the threaded end b' of the valve tube b is made as short as can be for the purpose intended, that is to say it is only long enough to permit the nut g to be threaded down to clamp the tongue on the nut e at which time the top surface of the nut g is about flush with the end of the threaded section b' . This relation is, of course, all in the interest of compactness so that no undue bulging of the ball at this point will result.

The threaded end b' is threaded interiorly also, as at b^8 to receive the stem h' of a valve cap h whose end h^2 is formed broad and flat but preferably slightly spherical so that when threaded down into the end of the valve stem it will add little in thickness to the devices protruding above the upper surface of the bladder a and its spherical finish will materially facilitate the lacing of the cover f over it, the edges of the cover adjacent the laced opening being adapted to ride up the spherical head h^2 and bear thereon. A transverse slot h^3 may be provided in the head for engagement by a coin or tool to assist in screwing the cap home.

Changes in details of construction and mere matters of form of design are to be deemed within the scope of the invention.

What I claim is:

1. In a valve for an inflatable device, a valve tube adapted to extend through an opening in a bladder and through an opening in an element of a cover and having a flange to engage one side of the bladder in proximity to the opening, the portion

of the tube adapted to extend through the opening being threaded, a nut on said threaded portion to clamp the bladder against the flange and a second nut on said threaded portion to clamp the element of the cover against the first nut. 55

2. In an inflatable device, a cover having an opening therein, a bladder having an opening therein, a valve tube having a threaded portion extending through the opening in the bladder and provided with a rimmed flange on the tube adapted to engage the inner side of the bladder adjacent the opening, a rimmed washer through which the threaded portion of the tube extends lying over the outer-side of the bladder adjacent the opening, a clamping nut threaded on to the tube and forcing the rimmed washer against the bladder to squeeze the latter against the flange and form an airtight union, the threaded portion of the valve tube extending through the opening in the cover and a clamping nut threaded on to the tube and clamping the cover against the first mentioned clamping nut to retain the bladder in proper position in the cover. 65 70 75

3. In an inflatable device, in combination with a cover having an apertured tongue and a bladder having a hole therein, a valve tube extending through the hole in the bladder and the aperture in the tongue, relatively movable devices associated with the valve tube to squeeze the rubber between the devices and clamp the tube in place with an airtight union, and other relatively movable devices associated with the valve tube to clamp the tongue on to the first mentioned clamping devices to maintain the bladder in proper position in the cover, said last mentioned clamping devices 80 85 lying nearly flush with the end of the valve tube, when in place, and a metal valve cap threaded into the end of the valve tube and having a broad flat head shaped spherically to lie under the cover. 90 95

This specification signed this 3d day of July A. D. 1923.

HENRY RIDGEWAY HART.
